UNITED STATES PATENT OFFICE

WILDER E. COBB, OF SALISBURY, NORTH CAROLINA, ASSIGNOR OF ONE-HALF TO
AUGUSTUS H. COBB, OF SALISBURY, NORTH CAROLINA

RAZOR BLADE SHARPENER

Application filed March 19, 1931. Serial No. 523,864.

This invention relates to improvements in sharpeners and pertains particularly to an improved design of safety razor blade sharpener.

5 The primary object of the present invention is to provide a crank operated safety razor blade sharpener in which both edges of the blade are rotated about a surrounding circular abrading surface to effect the quick 10 and easy sharpening thereof.

Another object of the invention is to provide a novel carrying means for the safety razor blade, by which it is held firmly in contact with the annular abrading surface, during 15 the use of the device.

Still another object of the invention is to provide a novel means for placing in and removing from position the blade holding unit of the present sharpener.

20 Other objects and advantages of the invention will become apparent as the description of the same proceeds, and the invention will be best understood from a consideration of the following detailed description taken in 25 connection with the accompanying drawing forming part of this specification, with the understanding, however, that the invention is not confined to any strict conformity with the showing of the drawing but may be 30 changed or modified so long such changes or modifications mark no material departure from the salient features of the invention as expressed in the appended claim.

In the drawing:—
35 Figure 1 is a central longitudinal sectional view through the sharpener embodying the present invention.

Figure 2 is a sectional view taken on the line 2—2 of Figure 1.

40 Figure 3 is a plan view of the blade carrying table of the device.

Referring more particularly to the drawing, wherein like numerals of reference indicate corresponding parts throughout the several views, the numeral 1 indicates generally 45 the housing or casing of the present sharpener, which casing is preferably formed of glass and also constitutes the abrading element against the inner surface of which the 50 razor blade to be sharpened is moved. In the

form of the invention as illustrated, the casing 1 is of cylindrical design and is closed at one end by a cover 2 which may be detachably mounted thereon, as indicated at 3, to facilitate the disassembly of the device. Extending through the end cover 2 is an elongated sleeve 4 which is disposed longitudinally of the cylinder casing 1 and upon the longitudinal center thereof, as illustrated.

Passing through the sleeve 4 is a shaft 5 which is of materially greater length than the casing and which has upon its forward end the head 6 which prevents its extraction from the sleeve 4 while upon its other end is mounted a crank 7.

Carried by and extending transversely of the shaft 5, at the inner end of the sleeve 4, is a pair of tubular arms 8 which extend radially from the shaft in the manner shown each of these arms being of a length, from 70 the shaft to its free end, materially less than the interior radius of the casing so that a substantial clearance area remains between the ends of the arms and the interior wall of the casing when the arms are positioned 75 therein, as during the performance of a blade sharpening operation.

In each of the arms 8 is a core 9 which is removable therein but is limited in this movement by a pin 10 which is disposed in a slot 80 11 formed longitudinally in the wall of the encasing arm. Between the inner end of each core 9, and the shaft 5, each arm houses a coil spring 12 which normally urges the 85 cores outwardly.

Connecting and carried by the cores 9 of the arms is a razor blade supporting table 13, the top surface of which is transversely arcuate, as illustrated, to conform to the arc 90 of the interior surface of the casing. This table has the major portion of the top or arcuate surface thereof inlaid with a suitable friction material 14, such as rubber or the like, to hold a blade in position thereon 95 and in addition to this the reduced portion of the outer end of each core 9 passes through the table, as indicated at 15, and projects above the surface of the material 14 to form a pin designed to engage in the slot found 100

in the particular types of blades for which the present device is designed.

In operation, the crank 7 is grasped and, with the casing 1 held in the other hand, the shaft 5 is pulled in a direction to move the table 13 out of the casing through the open end thereof. The head 6 upon the end of the shaft is so located that while the inlaid portion 14 of the table will be completely removed from the casing, a portion of the inner end of the table will remain therein so that no difficulty will be experienced in reinserting the table. Since the friction material 14 covers an area slightly greater than the size of a razor blade the blade may be readily placed upon the table in engagement with the pins 15, even though the table is not completely withdrawn from the casing, and after this is done then by forcing the table downwardly slightly against the tension of the springs 12 it may be easily reinserted into the casing and, as will be readily seen, the springs, forcing the table outwardly, will force the edges of the blade into firm contact with the inner surface of the casing. By rotating the crank 7 the shaft 5, and structure carried thereby, is also rotated so as to constantly move the blade over the inner surface of the casing against which it bears.

While the casing herein shown and described is preferably made of glass, it is, of course, to be understood that applicant does not wish to limit himself to this particular material as any other suitable material may be employed against which the razor blade is pressed, without departing from the spirit of the invention.

Having thus described the invention, what is claimed is:

A razor blade sharpener, comprising a body having an interior circular abrading surface of glass, a shaft extending longitudinally through the body upon the radial center of said surface, and supported for rotation, a tubular arm carried by said shaft within the casing and of a length less than the radius of the circular surface, a body reciprocable in said arm and normally projecting from the free end thereof, a blade carrying table supported by said body, resilient means within said arm, normally urging said body outwardly, said table having the outer surface thereof formed to support a razor blade with its edges in contact with the abrading surface, and said shaft having limited longitudinal movement and adapted to be removed from one end of the casing to also remove the blade supporting portion of the table therefrom.

In testimony whereof I hereunto affix my signature.

WILDER E. COBB.
